MATERIAL MIXING MACHINE

Harold H. Foltz, Cleveland, Ohio, assignor to The
Arco Company, Cleveland, Ohio, a corporation
of Ohio

Application March 26, 1945, Serial No. 584,878

2 Claims. (Cl. 259—54)

1

This invention relates to apparatus for storing, agitating and dispensing, as desired, different characters of paint or similar material, whereby any desired mixture may be readily obtained.

Power actuated paint mixing apparatus heretofore used has generally been of such size as to restrict the use thereof to relatively large users of paint materials, as a result of which, small users have been compelled to resort largely to hand methods of mixing materials. The hand method is objectionable not only from a viewpoint of the time consumed, but also in the lack of assurance of uniformity of mixture of the material in the individual can. Whenever a can remains unused for a short time, the heavier ingredients settle to the bottom, and there is a likelihood that the operator may forget to agitate the contents before withdrawing a portion thereof. There is a large demand for a small, compact machine that will enable the operator to use quart size cans, and to obtain comparable accuracy and efficiency in quality of mixture and in convenience of handling as may be obtained by the large power driven machine.

An object of the present invention, therefore, is to provide small sized equipment that will enable the use of quart cans in the machine and that will effect simultaneous agitation of the contents in a plurality of cans. The invention additionally includes a construction which will constitute a compact storage receptacle for the cans with provision for enabling any can to be selectively removed for dispensing a portion of the contents thereof without necessitating removal of the other cans or disturbing their operative connection with the agitating mechanism. An additional object is to provide a machine by means of which a driving connection is made automatically between an agitator device and a driving wheel whenever a container is interlocked with the carrier therefor.

In the drawings, Fig. 1 is a top plan view of a device embodying the present invention; Fig. 2 is a side view thereof; Fig. 3 is a section taken on a plane indicated by the line 3—3 in Fig. 2; Fig. 4 is a sectional view partly in elevation illustrating the container removed from the carrier; Fig. 5 is a section taken on a plane indicated by the line 5—5 in Fig. 4, and Fig. 6 is a section taken on a plane indicated by the line 6—6 in Fig. 1, but illustrating one container head removed from the carrier.

In the respective drawings, 10 indicates an upright frame which is shown as a hollow member having a partition 11 therein, and a cover plate

2

12 thereon. The plates 11 and 12 are apertured to receive a shaft 13 which is journalled for rotation with respect to the frame and which has affixed thereto a bevel gear 14 at the lower end, and a driving wheel 15 at the upper end thereof. The wheel 15 is adapted to make frictional engagement at its periphery with a plurality of driven wheels 16, each of which is supported for rotation within a head 17 that is adapted to be attached to a can, or other container, indicated in general at 18. Each driven wheel is attached to a shaft 19 that extends through the associated head 17 and carries an agitator 20 at the lower end thereof.

15 To actuate the drive shaft 13, I provide a bevel gear 21 that meshes with the gear 14, and is affixed to a shaft 22 that is journalled in the frame 10. A hand wheel 23 is shown as being affixed to the outer end of the shaft 22.

20 To support the various paint containers, I have shown a turntable or carrier 30 which is supported on the plate 12 and is rotatably mounted on the shaft 13. The carrier has a plurality of pockets 31 opening outwardly around the peripheral edge thereof, each of which is adapted to receive a paint container and to hold it in operative position for effecting a frictional driving connection between the wheels 15 and 16. This may be accomplished by pin and socket connections, the pins being indicated at 32 on the carrier, and the sockets at 33 on the head 17. There are two pin and socket connections for each container, and the connection is made by lifting the assembled head and container as a unit off the carrier as is shown in Figs. 4 and 6.

25 To effect a removable connection between each head and the associated container, I have shown a plurality of clamping members on each head, each member including a finger 35 which is affixed to a pin 36 that projects through the head and has a tool receiving slot 37 in one end thereof. The finger is adapted to engage frictionally the lower surface of a U-shaped flange 38 that is customarily utilized on paint cans for holding a removable cover thereon. In practice, the cover is removed and replaced by the head 17 which is handled as a unit with the driven wheel 16 and agitator 20 as aforesaid. Each head also has a spout 40 extending therefrom, and additionally, 30 preferably has a closure 41 therefor which may be swingably mounted thereon by means of a threaded retaining member 42.

35 To use the machine of the present invention, the liquid containers each having the head and agitating means assembled thereon are positioned

on the carrier by moving the sockets 33 into registration with the pins 32, and by then causing the pins to enter the sockets to effect an interlocking connection therebetween. The diameters of the wheels 15 and 16 are so chosen that when the interlocking connection is made between the carrier and container head, a frictional driving connection is simultaneously made between the driving and driven wheels. Then while the carrier is held in stationary position with respect to the frame 10 and the hand wheel 23 is rotated, the resultant action is a rotation of the agitator 20 in each container.

During the agitating process the container carrier may be held stationary, either by hand or by any suitable stop mechanism, one of which is illustrated in Fig. 1 as a pin 50 which is movably mounted on a housing partially indicated by the broken lines 51, and which is selectively insertable into the space between the pins 32 for adjacent heads. The pin may be manually withdrawn at any time for enabling the carrier to be turned by hand so as to present any desired container to the operator who may be standing in front of the machine. Whenever a can is removed, the contents of any portion thereof may readily be dispensed by holding the can in the hand and tipping it sufficiently to permit the material to flow through the spout. Then when the can is replaced, the device functions as a storage unit until the can is emptied, whereupon it may be replaced by removing the head and associated agitator mechanism from the empty can and attaching it to a filled can.

A mixing machine made according to the present invention is advantageous in that it makes available to a relatively small user, a device for effecting thorough simultaneous agitation in a plurality of small size cans, and in that it operates to achieve the desired result in an expeditious manner without necessitating transfer of the material from the standard to a special container.

I claim:

1. In a liquid mixing, storage and dispensing device, the combination comprising: a frame; a primary shaft vertically supported within and by said frame for rotation with respect thereto; a disk-like, horizontally-placed turntable co-axially encircling said primary shaft and freely rotatable with respect thereto and a bearing on said frame rotatably supporting said turntable; a plurality of individual containers having a removable supporting cover member associated therewith; said turntable having a plurality of peripheral recesses each of size and shape to snugly receive one of said containers and cover engaging means on the upper side of said turntable adjacent each of said recesses for removably engaging and holding one of said supporting covers within each of said recesses; each of said cover member's supporting a rotatable secondary shaft having an agitator on one end within the respectively-associated container and a driveable wheel at its other end outside of said respectively-associated container; a driving wheel on said primary shaft supported by said turntable and freely rotatable with respect to said turntable, said driving and driveable

wheels being of such respective diameters that they will engage each other on a circle lying, with respect to the turntable, near the radially innermost parts of the said containers for frictional driving of the driveable wheel by the driving wheel; means for rotating said primary shaft, whereby rotation of said primary shaft will rotate said turntable when same is free to rotate and will rotate said agitators when said turntable is held against rotation and any container may be freely inserted into place or removed therefrom without tilting at any time when said turntable is non-rotating regardless of whether the primary shaft is rotating.

2. In a liquid mixing, storage and dispensing device, the combination comprising: a frame; a primary shaft vertically supported within said frame for rotation with respect thereto; a disk-like, horizontally-placed turntable co-axially encircling said primary shaft and freely rotatable with respect thereto and a bearing on said frame rotatably supporting said turntable; a plurality of individual containers having a supporting cover member associated therewith; said turntable having a plurality of peripheral recesses each of size and shape to snugly receive one of said containers and cover engaging means on the upper side of said turntable adjacent each of said recesses for removably engaging and holding one of said supporting covers within each of said recesses; each of said cover members supporting a rotatable secondary shaft having an agitator on one end within the respectively-associated container and a driveable wheel at its other end outside of said respectively-associated container; a driving wheel on and supporting said primary shaft and supported by said turntable and freely rotatable with respect to said turntable, said driving and driveable wheels being of such respective diameters that they will engage each other on a circle, lying with respect to the turntable, near the radially innermost parts of the said containers for frictional driving of the driveable wheel by the driving wheel; means for rotating said primary shaft, whereby rotation of said primary shaft will rotate said turntable when same is free to rotate and will rotate said agitators when said turntable is held against rotation and any container may be freely inserted into place or removed therefrom without tilting at any time when said turntable is non-rotating regardless of whether the primary shaft is rotating.
